LOCKER DOOR HANDLE

Joop M. Van Ryn, Whitby, Ontario, Canada, assignor to
The Pedlar People Limited, Oshawa, Ontario, Canada

Filed Apr. 15, 1970, Ser. No. 22,436

Claims priority, application Canada Feb. 2, 1970

Term of patent 14 years

Int. Cl. D8—06, 07

U.S. Cl. D8—148

The figure is a perspective view of a locker door handle with a portion of a locker door shown in broken lines for illustrative purposes only.

The undisclosed right side of the hand grip member is similar in appearance to the side shown.

I claim:

The ornamental design for a locker door handle, as shown and described.
